UNITED STATES PATENT OFFICE.

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed September 3, 1926. Serial No. 133,343.

This invention relates to means for facilitating the handling of work-sheets in type-writing machines.

The problem which is solved by means of this invention is that of copying in a condensed form on a record-sheet only the first line typed upon a statement-sheet upon which other lines of typing are also written.

A concrete example of such a problem is illustrated where it is desired to send out a statement to each one of a list of patrons, said statement having both a typed line of financial statement and the name and address of the patron as well, and a condensed record is desired of the financial statement line without simultaneous record of the name and address being made. The advantage gained by the present solution of this problem is that the act of typing the statement-sheet also makes the office record, so that the same is done without separately filling out an address and statement-sheet thereafter, and, in addition, errors are also immediately subject to rectification, as it is at once seen from the record what figures appeared on any statement sent out.

A two-ply record-sheet with carbons is inserted at the rear of the platen and set to the printing line. The record-sheets are laterally positioned by means of a front table, upon which is a series of movable shields. Said shields are interleaved between the record-sheets and carbons and are normally held in ineffective position so that the lower edges thereof are above the printing line, thus permitting typing upon all the record-sheets.

The record-sheets are held in place by means of two front feed-rolls bearing on the projecting side edges thereof, while the regular feed-rolls are released for the purpose of permitting front insertion of a narrow statement-sheet. The latter is positioned for the first line of typing by the aid of the usual wing scales, and then the feed-rolls are restored and the first line of typing is copied on the record-sheets. Then the shields are lowered to cover the printing line and prevent further typing on the record-sheets. Several other lines of typing are then writ-

ten on the statement-sheet, which do not appear on the record-sheets.

In order that the first line of typing on the next statement-sheet may appear on the record-sheet in a condensed manner near the other line of typing, there is provided mechanism mounted at the end of the platen for the purpose of retracting the record-sheet to a position for receiving the second line of typing thereon. It will be understood that according to this invention the record-sheet and the statement-sheet are first simultaneously line-spaced a predetermined number of line-spaces, and that the record-sheet is then retracted the same number of line-spaces except one.

One of the features of this invention relates to means for positively holding the shields in their ineffective position. To this end, there are provided a pair of clamps which engage the under side of projecting finger-pieces forming an integral part of the shields. All the shields are operated simultaneously and are temporarily held in place by means of flat springs during the operation of the clamps.

Other features and advantages will hereinafter appear.

In the accompanying drawings,

Figure 1 is a front view, in elevation, of part of an Underwood typewriting machine having the invention applied thereto. The work-sheets are shown in a position to receive the first line of typing thereon.

Figure 2 is a similar view showing the work-sheets in a position for receiving the second line of typing thereon.

Figure 3 is an end view, partly in cross-section, showing the work-sheets in the position shown in Figure 1.

Figure 4 is a diagrammatic view illustrating the position of the shields when the work-sheets are positioned for the second line of typing.

Figure 5 is a diagrammatic view illustrating the differential line-spacing mechanism.

Figure 6 is a diagrammatic view showing the work-sheets in a position for receiving the last line of typing thereon.

Figure 7 is a diagrammatic view showing

the relative positions of the work-sheets after retracting the platen and prior to removing the typed statement-form from the machine.

Figure 8 shows one of the forms which may be used in connection with this invention.

This invention is especially adapted for filling in, in a typewriting machine, a statement-form such as illustrated in Figure 8 and generally indicated by the numeral 10, and for obtaining a condensed copy of some of the data appearing thereon on a plurality of record-sheets 11.

It is desired to first type upon the form a line of data 12, which is to be copied upon the record-sheets by means of intervening carbons 13, and then several other lines of data which do not appear on the record-sheets. The second line of data 14 indicates, in this instance, the location of the mortgaged property, while the last three lines of typing represent the name and mailing address, and are typed in a space 15 visible through a transparent window when the form is placed in an envelope.

The record-sheets are interleaved with the carbons and the pack is inserted at the rear of a platen 16 and held against displacement by means of feed-rolls 17 engaging the edges thereof. During typing the record-sheets are fed around the platen by means of feed-rolls 18, but these are released to permit the front insertion of the statement-sheet or form 10, which is positioned by means of winged scales 19.

In order that only a portion of the typing appearing upon the form 10 may be copied upon the record-sheets, there are provided a plurality of non-print shields 20 slidably mounted on a front table 44. The shields are designed to be interleaved between each carbon and its associated record-sheet to thereby prevent typing upon the record-sheet. Normally, however, the shields are held in their ineffective positions, as shown in Figure 1, so that the bottom edges thereof are above the printing line. The shields are held in their ineffective positions by means of clamps 21 which engage the under side of finger-pieces 22 forming an integral part of the shields. While thus holding the shields the feed-rolls 18 are cast on and the first line of typing 12 is written upon all the work-sheets by means of type-bars 23 and the carbons 13. The platen is the line-spaced and the carriage is returned by means of a line-spacing lever, not shown, but operatively connected to a ratchet 24 carried by a shaft 25 upon which the platen is mounted. This line-spacing and carriage-return movement is effective to position the work-sheets for the second line of typing 14 as indicated in Figure 4.

At this time the shields 20 are lowered to the position shown in Figure 4 so that the

lower edge thereof is below the last line to be typed upon the form. The second line of typing may then be typed and the platen line-spaced in the regular manner to position the same for other lines of typing. It will be noted that these lines of typing are not copied upon the record-sheets because the shields have been lowered to cover the printing line. During the line-spacing movement of the platen the shields are carried along with the work-sheets, as shown in Figures 3 to 6, inclusive. After typing the last line upon the statement-form, the carriage is returned to its normal position and the platen is automatically line-spaced. The statement is then withdrawn and the shields are elevated to their ineffective or non-shielding position.

The shields are raised by gripping the finger-pieces 22 and are pushed under springs 26 and against stops 27. The springs hold the shields temporarily while the clamps 21 are swung to their effective position, as shown in Figure 3, by means of a finger-piece 28 fast to a cross-shaft 29 upon which the clamps 21 are secured by means of screws 30. The shaft is journaled in brackets 31, which are secured to end plates 32 by means of screws 33.

Upon occasion it may be desired to hold the shields in effective lowered position, as, for example, when the work-sheets are much longer than the shields. The latter might then be line-spaced upward to ineffective position if considerable typing were done, and the typing would then appear on the record-sheets, although not desired. In such a case it is but necessary to swing the clamps 21 forward to effective, obstructive or clamping position when the shields have been lowered to their effective position, in order to retain the shields in said lowered position and prevent them from being line-spaced with the work-sheets, or manually raised, until the clamps have been released.

According to some of the features of this invention, it is not only desired to copy the first line of typing on each form upon the record-sheets, but to copy the lines in a condensed form so as to crowd as many lines as possible upon each record-sheet. To this end, it has been found desirable to retract the platen to a position corresponding to the next line of typing on the record-sheets, since the latter have been line-spaced along with the statement-form when typing thereon. The retracting movement of the platen is quickly accomplished by operating a handle 34 mounted on the platen-shaft 25. When the first line is typed the handle is positioned against a stop-pin 35, and since the handle is operatively connected to a ratchet-wheel 36, carried by the shaft 25, by means of a pawl 37 held in engagement therewith by a cam-ring 38, the handle will

move along with the platen when the same is line-spaced. The successive line-spacing positions of the platen and corresponding positions of the handle are illustrated in Figures 3 to 7, inclusive. It will be noted that while the platen is line-spaced seven spaces it is desired to retract the platen only six spaces so as to bring the record-sheet in a position to receive a second line of typing one line-space below the first. This differential movement of the platen is automatically obtained when the handle 34 reaches the position shown in Figure 4, at which time the pawl 37 is thrown out of engagement with the wheel 36 by the action of a spring 39 which forces the back of the pawl into a groove 40 in the inner face of the cam-ring 38. Since this disengagement of the pawl and wheel occurs when typing the line previous to the last line indicated by the numeral 41, a subsequent line-spacing movement of the platen is effective to move the ratchet one tooth ahead of the pawl, so that when the handle is swung to retract the record-sheets, the pawl has escaped one tooth and the platen is rotated backwardly one space less than it was fed in line-space direction.

In order that the clamps 21 may be held in either effective or ineffective position, there is provided a spring 42 fast to the finger-piece 28 which engages notches 43 cut in one of the brackets 31. The effective and ineffective positions of the clamps are respectfully indicated in Figures 3 and 4.

The front table 44 is adjustably mounted on a cross-bar 45 carried by the brackets 31. The extreme uppermost and lowermost positions of the shields 20 are limited by upper tabs or stops 27 and by the lower stops 46 which interpose the finger-pieces 22.

Since the table is adjustable to accommodate record-sheets of different widths, it has been found advisable to mount the front feed-rolls 17 so as to permit adjustment thereof. To this end, each feed-roll is carried by a deflector-spring 47 which is fast to a bracket 49 slidably mounted on a cross-shaft 48.

Sometimes it may be desired to obtain a copy in full of the statement-sheet. In order to facilitate handling of this copy sheet it is proposed to provide a backing 50 which is attached to the original statement-sheet by a weakened line of perforations. A carbon-sheet 51 is inserted between the sheets and the pack is then front inserted, bottom edge first.

Variations may be resorted to within the scope of the invention, and portions of the improvements may be used without others.

Having thus described my invention, I claim:

1. In a typewriting machine, the combination of a revoluble platen, a line-space-lever therefor, front feed-rolls for holding a plurality of record-sheets against the platen, a

plurality of shields for interposing each record-sheet at the printing line, means for normally holding the shields so that the lower edges thereof are above the printing line, a front inserting device for positioning a statement-sheet in front of the record-sheets, reusable feed-rolls for simultaneously feeding all the work-sheets, the shields being lowered in front of the record-sheets to prevent typing thereon after typing the first line, and means for retracting the record-sheets to a position for receiving a second line of typing thereon.

2. A typewriting machine including, in combination, a revoluble platen, a table at the delivery side thereof for positioning work-sheets, a plurality of shields slidably mounted on said table for interleaving the work-sheets and preventing typing thereon, and means for positively holding the shields in a position to permit typing upon the work-sheets.

3. A typewriting machine including, in combination, a revoluble platen, a table at the delivery side thereof for positioning work-sheets, a plurality of shields slidably mounted on said table for interleaving the work-sheets and preventing typing thereon, means for positively holding the shields in a position to permit typing upon the work-sheets, said means including a pair of clamps pivotally mounted on said table, and resilient means for holding the clamps in either their effective or ineffective positions.

4. A typewriting machine including, in combination, a platen, a table at the delivery side thereof for positioning work-sheets, a plurality of shields slidably mounted on said table for interleaving the work-sheets and preventing typing thereon, means for positively holding the shields in a position to permit typing upon the work-sheets, said means including a bracket for supporting the table, a cross-shaft journaled in said bracket, a pair of clamps carried by said shaft, the clamps engaging the under side of finger-pieces extending from the shields, a finger-piece for rocking the shaft to thereby swing the clamps to either effective or ineffective positions, and resilient means for holding the shaft in either its effective or ineffective positions.

5. A typewriting machine including, in combination, a platen, a table at the delivery side thereof for positioning work-sheets, a plurality of shields slidably mounted on said table for interleaving the work-sheets and preventing typing thereon, means for positively holding the shields in a position to permit typing upon the work-sheets, said means including a bracket for supporting the table, a cross-shaft journaled in said bracket, a pair of clamps carried by said shaft, the clamps engaging the under side of finger-pieces extending from the shields, a finger-

- piece for rocking the shaft to thereby swing the clamps to either effective or ineffective positions, and resilient means for holding the shaft in either effective or ineffective positions, said last-mentioned means including a spring-member carried by the finger-piece, the spring-member having a detent at the end thereof for engaging with positioning notches in the bracket.
10. 6. A typewriting machine including, in combination, a platen, a table at the delivery side thereof for positioning work-sheets, a plurality of shields for interleaving the work-sheets at the printing line and preventing typing thereon when the shields are moved below the printing line, and means for normally holding the shields in their ineffective position above the printing line in a manner to permit typing upon the work-sheets, said means including resilient means for temporarily holding the shields in their uppermost position, and means for positively locking the shields in their ineffective position.
15. 7. In a typewriting machine, the combination of a revoluble platen, a table at the delivery side thereof for laterally positioning a plurality of record-sheets having interleaved carbons, and a carbon for typing upon the first record-sheet, a shield between each carbon and each record-sheet, finger-pieces for manipulating the shields, and means for guiding and positioning the shields in either their uppermost or ineffective position, or in their lowermost or effective position.
20. 8. In a typewriting machine, the combination of a revoluble platen, a table at the delivery side thereof for laterally positioning a plurality of record-sheets having interleaved carbons, and a carbon for typing upon the first record-sheet, a shield between each carbon and each record-sheet, said shields being normally held in their ineffective position above the printing line but being movable to cover the printing line and prevent typing upon the record-sheets, a front insertion device for collating a statement-sheet in front of the record-sheets, and feed-rolls for holding the sheets during typing and for simultaneously line-feeding all the sheets, the shields being lowered to cover the printing point after the first line of typing so that subsequent lines of typing will appear on the statement-sheet only.
25. 9. In a typewriting machine, the combination of a revoluble platen, a table at the delivery side thereof for laterally positioning a plurality of record-sheets having interleaved carbons, and a carbon for typing upon the first record-sheet, a shield between each carbon and each record-sheet, said shields being normally held in their ineffective position above the printing line but being movable to cover the printing line and

prevent typing upon the record-sheets, a front insertion device for collating a statement-sheet in front of the record-sheets, feed-rolls for holding the sheets during typing and for simultaneously line-feeding 70 all the sheets, the shields being lowered to cover the printing point after the first line of typing so that subsequent lines of typing will appear on the statement-sheet only, and means for retracing the platen so as to automatically position the record-sheets for a line of typing one space below the line previously typed upon the record-sheets.

10. In a typewriting machine, the combination of a revoluble platen, a carriage therefor, a line-spacing mechanism, a platen-retracting mechanism for said platen, and a front table for positioning and guiding a statement-sheet and a plurality of record-sheets, each record-sheet having an associated shield to prevent typing thereon, the bottom edges of said shield being normally above the printing line but being movable to cover the record-sheet so that after typing the first line other lines of typing may be 90 shielded from the record-sheet, the platen-retracting mechanism being effective to position the record-sheets so that the first line of typing on a second statement-sheet will be copied on the record-sheet as the second line 95 of typing thereon.

11. In a typewriting machine, the combination of a revoluble platen around which are fed a statement-sheet and one or more record sheets with carbons interleaved between adjacent sheets, means for preventing the copying onto the record-sheets of a portion of the matter typed on the statement-sheet, and means for retracting the record-sheets a predetermined number of spaces less 105 than the number of blank spaces they have been advanced, in order to position them to receive the next line of typing of the next statement-sheet close to the last one of the preceding statement-sheet in order to produce a condensed record, said first-mentioned means including one or more shields, each disposed forwardly of a record-sheet and movable over the printing line to prevent copying on said record-sheets and away from 110 said printing line to permit copying on said sheets, means for holding said shields in operative position, and means for holding said shields in inoperative position.

12. In a typewriting machine, the combination of a revoluble platen around which a plurality of work-sheets with interleaved carbons are arranged to be fed, one or more shields movable substantially vertically for interleaving the work-sheets and preventing 125 typing thereon, means for holding said shields in operative position, and means for holding the same in inoperative position.

13. In a typewriting machine, the combination of a revoluble platen around which a 130

- plurality of work-sheets with interleaved carbons are arranged to be fed, one or more shields movable substantially vertically for interleaving the work-sheets and preventing 5 typing thereon, tabs on said shields extending laterally therefrom and beyond the side edges of the work-sheets, and means co-operating with said tabs to hold the shields in operative and in inoperative position.
- 10 14. A typewriting machine including the combination with a carriage, a revolute platen thereon, and means to feed work-sheets interleaved with a carbon about the platen, including feed-rolls, of a shield interleaved with said work-sheets and both 15 manually shiftable down into effective position at the delivery side of the platen in a plane relatively tangent thereto in order to cover the printing line and thereby prevent 20 typing through said carbon, and also shiftable upward in said plane to ineffective position in order to permit typing through said carbon, and means to determine the ineffective and effective positions of said shield 25 including stop-members rigidly supported on said carriage and spaced apart in such manner as to constitute upper and lower stops for said shield.
15. A typewriting machine including the combination with a carriage and a revolute platen thereon, of a paper-table mounted on the carriage at the delivery side of the platen for positioning work-sheets, said work-sheets being interleaved with a carbon and feedable 30 by said platen, a non-print shield supported on said table in interleaved relation with said work-sheets and both slidable along the table down into effective position so as to cover the printing line on the platen in order to prevent typing through said carbon, and also slidable on 35 said table up to ineffective position to permit typing through said carbon, means for positively retaining the shield in effective position or ineffective position on said table, and means to locate said shield in either 40 position.
19. A typewriting machine including the combination with a carriage and a revolute platen thereon, of a paper-table mounted on the carriage at the delivery side of the platen for positioning work-sheets interleaved with a carbon and feedable by said platen, a non-print shield supported on said table in interleaved relation with said work-sheets and both slidable along the table down into effective position so as to cover the printing 45 line on the platen in order to prevent typing through said carbon, and also slidable on said table up to ineffective position to permit typing through said carbon, and means for positively retaining the shield in ineffective position, including manually releasable clamps associated with the table for engaging said shield when in raised position upon said table.
16. A typewriting machine including the combination with a carriage and a revolute platen thereon, of a paper-table mounted on the carriage at the delivery side of the platen for positioning work-sheets interleaved with a carbon and feedable by said platen, a non-print shield supported on said table in interleaved relation with said work-sheets and both slidable along the table down into effective position so as to cover the printing line on the platen in order to prevent typing through said carbon, and also slidable on said table up to ineffective position to permit typing through said carbon, and means for frictionally retaining the shield independently of said work-sheets in ineffective position when raised on said table, including resilient clamping members associated with the table.
17. A typewriting machine including the combination with a carriage and a revolute platen thereon, of a paper-table mounted on the carriage at the delivery side of the platen for positioning work-sheets interleaved with a carbon and feedable by said platen, a non-print shield supported on said table in interleaved relation with said work-sheets and both slidable along the table down into effective position in order to cover the printing line and thereby prevent typing through the carbon, and also slidable on said table up to ineffective position in order to expose the printing line and permit typing through said carbon, and means whereby said shield may be moved along said table independently of said work-sheets.
18. A typewriting machine including the combination with a carriage and a revolute platen thereon, of a paper-table mounted on the carriage at the delivery side of the platen for positioning work-sheets interleaved with a carbon and feedable by said platen, a non-print shield supported on said table in interleaved relation with said work-sheets and both slidable along the table down into effective position so as to cover the printing line on the platen in order to prevent typing through said carbon, and also slidable on said table up to ineffective position to permit typing through said carbon, means for positively retaining the shield in effective position or ineffective position on said table, and means to locate said shield in either position.
19. A typewriting machine including the combination with a carriage and a revolute platen thereon, of a paper-table mounted on the carriage at the delivery side of the platen for positioning work-sheets interleaved with a carbon and feedable by said platen, a non-print shield supported on said table in interleaved relation with said work-sheets and both slidable along the table down into effective position so as to cover the printing line on the platen in order to prevent typing through said carbon, and also slidable on said table up to ineffective position to permit typing through said carbon, and means for positively retaining the shield in ineffective position, including manually releasable clamps associated with the table for engaging said shield when in raised position upon said table.
20. A typewriter machine including the combination with a carriage and a revolute platen thereon, of a paper-table mounted on the carriage at the delivery side of the platen for positioning work-sheets interleaved with a carbon and feedable by said platen, a non-print shield supported on said table in interleaved relation with said work-sheets and both slidable along the table down into effective position so as to cover the printing line on the platen in order to prevent typing through said carbon, and also slidable on said table up to ineffective position to permit typing through said carbon, and means for positively retaining the shield in ineffective position, including manually releasable clamps associated with the table for engaging said shield when in raised position upon said table.

the printing line on the platen in order to prevent typing through said carbon, and also slidable on said table up to ineffective position to permit typing through said carbon, and means for positively retaining the shield in effective or ineffective position on the table, including manually operable mem-

bers associated with said table and arranged to be both movable to obstructive position relative to the shield in order to fix the same in either position, and also movable to free said shield for independent movement upon said table. 10
